PORTABLE SPACE HEATER

William M. Cooper, St. Louis, Mo., assignor to Champion Heater Co. Inc., St. Louis, Mo., a corporation of Missouri

Application February 3, 1958, Serial No. 49,482

Term of patent 14 years

(Cl. D81—19)

Fig. 1 is a top plan view of a portable space heater showing my new design;

Fig. 2 is a front elevational view of the said heater;

Fig. 3 is a side elevational view of the said heater; and

Fig. 4 is a rear end elevational view of the said heater showing my new design.

I claim:

The ornamental design for a portable space heater, substantially as shown.
